UNITED STATES PATENT OFFICE.

DALRIDGE B. BEAVERS AND PATRICK D. BEAVERS, OF WASHINGTON, DISTRICT OF COLUMBIA.

WIRE REEL.

Application filed December 23, 1921. Serial No. 524,474.

To all whom it may concern:

Be it known that DALRIDGE B. BEAVERS and PATRICK D. BEAVERS, citizens of the United States, residing at Washington, in 5 the District of Columbia, have invented new and useful Improvements in Wire Reels, of which the following is a specification.

Our said invention is designed more particularly as an improvement on the wire reel disclosed in the contemporary application of Dalridge B. Beavers, filed September 21, 1921, Serial Number 502,213, and in common with the invention of said application, the present invention has for one of its 15 objects to provide a reel constructed to handle coils of wire, more particularly cross-connecting or jumper wires in telephone central office terminal rooms, the present invention being quick acting for the expeditious expansion of the reel in a wire coil and for the ready contraction of the reel for the removal of the coil and the mounting on the reel of a fresh coil.

Another object of the present invention is 25 the provision of means in a reel to adapt the same for use in a coil of wire the bore or central opening of which is of conical or taper form.

To the attainment of the foregoing and 30 other objects hereinafter developed, the invention consists in the improvement as hereinafter described and definitely claimed.

In the accompanying drawings, forming part of this specification:—

Figure 1 is a side elevation of our improved reel.

Figure 2 is a top plan of the same.

Figure 3 is an enlarged cross section taken in the plane indicated by the line 3—3 of 40 Figure 2.

Figure 4 is an enlarged detail cross section taken on the line 4—4 of Figure 2.

Figure 5 is an enlarged detail cross section showing the connection of the reel 45 blades to one of the heads of the reel.

Figure 6 is an enlarged detail longitudinal section taken on the line 6—6 of Figure 2.

Figure 7 is a detail longitudinal section on 50 an enlarged scale showing modified retracting means.

Figure 8 is an enlarged detail fragmentary perspective showing the construction of reel blades designed more especially for

use in coils of wire with conical or tapered 55 central openings.

Figure 9 is a detail edge elevation at right angles to Figure 8.

Similar numerals designate corresponding parts in Figures 1 to 6 to which reference 60 will first be made.

Among other elements our improved reel comprises a bracket or frame, designed to be associated with any appropriate support (not shown). The said bracket or frame 65 includes longitudinal bars 1 in spaced and parallel relation, end bars 2 and 3, and intermediate cross bars 4 and 5. Mounted in the rear portion of the said bars 1 is a transverse bolt 6 secured in position by nuts 7, 70 and mounted on the said bolt 6 is a circumferentially grooved wheel 8 to which is fixed a spur gear 9, said wheel and gear being preferably formed in one piece to rotate as a unit about the bolt or shaft 6. 75 Coiled above the bolt or shaft 6 is a torsional spring 10, one end of which is connected at 11 to one bar 1 and the other end of which is connected at 12, Figures 3 and 6, to the gear 9. Manifestly when the spur gear 9 is rotated in one direction the spring 10 will be put under tension, and when the said spur gear is released the said spring 80 will operate to powerfully rotate the spur gear in the opposite direction. For the convenient turning of the wheel 8 in order to tension the spring 10 we provide the cable 12 seated in the circumferential groove 85 of the wheel 8, and connected at 13 thereto, and passed through a guide opening 14 in an arm 15 on a sub-bracket 16 carried by 90 one of the frame bars 1. The said guide serves to retain the cable 12 on the wheel 8 and against casual displacement, and in this the guide is assisted by a coiled spring 17, Figure 1, arranged about the extended portion of the cable 12 and interposed between the arm 15 and the handle 18 on the cable.

Freely movable through the frame bars 2, 5, 4 and 3 is a longitudinally movable 100 plunger rod 19 on which is fixed a collar or abutment 20. The said rod 19 is toothed for a portion of its length as designated by 21, and is provided at its forward end with a circular hub or disk 22, the said disk 22 being circumferentially grooved at 23 to seat a wire 24, Figure 5, through the medium of which the forward ends of the reel 105

blades 25 are preferably connected in pivotal manner to the head or hub 22. Other reel blades 26, Figure 1, are pivotally connected to the blades 25 at 27, and are pivotally connected at their rear ends and in the manner specifically described with reference to Figure 5, to a head or hub 28, which latter is connected in fixed manner to a sleeve 29, journaled in the box 30 provided between the frame bars 4 and 3. Surrounding the rod 19 and interposed between the forward end of the said sleeve 29 and the rear side of the forward head or hub 22 is a coiled expansion spring 31. The said spring 31 tends to move the head or hub 22 and the rod 19 forwardly, and therefore its function is to quickly contract the reel or reduce the same to the state shown by full lines in Figures 1 and 2 so as to permit of a coil of wire being readily placed on the reel blades. When the plunger rod 19 is retracted against the action of the spring 31, the blades 25 and 26 of the reel will be expanded so as to firmly bind the coil of wire, represented by dotted lines in Figures 1 and 2, on the reel blades, the said blades being crowded against the wall of the central opening through the coil of wire. For the said retraction of the plunger rod 19 we provide the rack bar 32, intermeshed with the support gear 9 and carried by a sleeve 33 which loosely receives the plunger rod 19 and is designed to act rearwardly against the collar or abutment 20 thereon. In order to prevent both the plunger rod 19 and the rack bar from moving about a common axis we provide the longitudinal guide rod 34 interposed between and carried by the frame bars 2 and 5. In order to lessen noise in operation we prefer to employ soft washers 35 and 36 on the plunger rod 19 back of and in front of the sleeve 33, respectively.

After the plunger rod 19 is retracted as described to expand the reel blades 25 and 26 it is necessary to detachably secure the plunger rod 19 in its retracted position in order to retain the reel blades in the expanded position. For this purpose we employ the 45 detent 40 best shown in Figure 4, the said detent being movable rectilinearly in a housing 41 fixed to the frame bar 5, and being provided with an appropriate handle 42 and backed by a spring 43, the said spring tending to yieldingly hold the inner end of the 50 detent 40 in engagement with the toothed portion 21 of the plunger rod 19 and the said inner end being shaped as shown to conform to the character of teeth illustrated. In the upper side of the rack bar sleeve 33 is provided an oiling opening 50.

It will be readily understood from the foregoing that when the reel blades 25 and 26 are contracted as shown by full lines in Figures 1 and 2, a coil of wire may be expeditiously and easily placed on or removed

from said blades. When a coil of wire is placed on the contracted blades 25 and 26 and it is desired to expand the blades to enable the same to engage and securely hold the coil of wire, it is simply necessary for 70 the operator to strongly pull on the handle 18 in the direction indicated by arrow in Figure 1 when by the rotation of the wheel 8 and the gear 9 and the retraction of the rack bar 32 and sleeve 33, the plunger rod 75 19 will be retracted, the latter being due to the action of the rack bar sleeve 33 against the abutment or collar 20 on the plunger rod 19. At this point it will be noticed that the abutment or collar 20 is provided with 80 an eye, to receive the rod 34 to prevent turning of the plunger rod 19. When the plunger rod 19 is retracted and the spring 31 is put under tension, the teeth 21 of the plunger rod will ride idly past the detent 85 40. When, however, the pull on the handle 18 in the direction indicated is stopped, the detent by engaging one of the teeth 21 will strongly hold the plunger rod 19 against forward movement and in that way will 90 maintain the reel blades 25 and 26 in an expanded position. When it is desired to bring about contraction of the reel blades 25 and 26 under the action of the spring 31 it is simply necessary for the operator to 95 draw on the detent handle 42 in the direction indicated by arrow in Figure 1 when the detent will be disengaged from the teeth of the rod 19, and the said rod will be left free for forward movement. Manifestly 100 when the detent 40 is disengaged from the teeth 21 as indicated the contraction of the reel blades 25 and 26 will be quickly effected, the same attending the quick expansion of 105 the spring 31.

In Figure 7 we illustrate a modified means for retracting the rack bar 3^a. The said means includes a handle 18^a on which is a sector gear 9^a, the latter being intermeshed with the teeth of the rack bar, and being connected to one end 12^a of a torsion spring 10^a, the opposite end 11^a of which is connected to the frame. 110

The described retraction of the rack bar 32 or 3^a tensions the spring 10 or 10^a which serves on the release of the handle to move the rack bar forwardly so that the said rack bar will not interfere with the subsequent movement of the plunger rod 19 when the detent 40 is disengaged therefrom. 115

When coils of wire with central openings of cone formation are to be handled we prefer to employ reel blades 25^a and 26^a such as shown in Figures 8 and 9, the said blades 25^a and 26^a being coupled by a double clip 120 60 the members of which are pivoted on a pintle 63, Figure 9, and through which each of the blades 25^a and 26^a is slidably in the direction of its length. We also provide between the arms of the blades 25^a and 26^a piv- 125 130

oted links one of which is shown by full lines in Figure 8 and designated by 61. Manifestly when blades such as 25^a and 26^a connected to the hubs or heads 22 and 28 are 5 expanded, the links 61 complementary to each pair of blades 25^a and 26^a will assume the inclined position shown by such lines in Figure 8 so as to conform to and snugly fit the wall of a conical opening in a coil of 10 wire. The link 61 is notched at 64 to receive the pintle 63 when the blades are in parallelism as when the reel is collapsed.

The link 61^x shown by dotted lines in Figure 8 is used interchangeably with respect to the link 61, said link 61^x being employed when a coil of wire with a central opening of even diameter is to be supported.

It will be apparent from the foregoing that notwithstanding the facility with 20 which our novel reel can be manipulated, the reel as a whole is simple and inexpensive in construction and is well adapted to withstand the rough usage to which devices of corresponding character are ordinarily 25 subjected. It will be also apparent from the foregoing that the carrying means of the reel formed by the hubs and blades is freely rotatable with the sleeve 29 about the center formed by the plunger rod 19, 30 and this notwithstanding said carrying means is contracted or expanded. It will be noticed, however, that when the carrying means is expanded and the spring 31 is under tension, the said spring will operate 35 after the manner of a brake to prevent too free rotation of the carrying means.

The construction illustrated and described has been reduced to actual practice and has been successfully operated, and we therefore prefer the said construction with all 40 of the details described. We do not desire, however, to be understood as confining ourselves to the specific construction and relative arrangement of the elements as in the 45 further practice of the invention such changes or modifications may be made as fairly fall within the scope of our invention as defined in our appended claims.

Having described our invention, what we 50 claim and desire to secure by Letters-Patent, is:

1. The combination in a reel, of coil carrying means capable of expansion and contraction, a frame, a toothed plunger rod 55 movable lengthwise in the frame and connected to a part of the carrying means and supporting said means, a spring on the rod and bearing against said part, and a detent to detachably hold the plunger rod in re- 60 tracted position.

2. The combination in a reel, of coil carrying means capable of expansion and contraction, a frame, a toothed plunger rod 65 movable lengthwise in the frame and connected to a part of the carrying means and

supporting said means, a spring on the rod and bearing against said part, a detent to detachably hold the plunger rod in retracted position, a movable member arranged to act against an abutment on and 70 retract the plunger rod, and means operable by an attendant to move said movable member.

3. The combination in a reel, of coil carrying means capable of expansion and 75 contraction, a frame, a toothed plunger rod movable lengthwise in the frame and connected to a part of the carrying means and supporting said means, a spring on the rod and bearing against said part, a detent to 80 detachably hold the plunger rod in retracted position, a movable rack arranged to act against an abutment on and retract the plunger rod, and a gear intermeshed with 85 said rack and operable by an attendant.

4. The combination in a reel, of coil carrying means capable of expansion and contraction, a frame, a toothed plunger rod movable lengthwise in the frame and connected to a part of the carrying means and 90 supporting said means, a spring on the rod and bearing against said part, a detent to detachably hold the plunger rod in retracted position, a movable member arranged to act against an abutment on and 95 retract the plunger rod, the rod movable through said member, and means operable by an attendant to move said movable member.

5. The combination in a reel, of coil carrying means capable of expansion and 100 contraction, a frame, a toothed plunger rod movable lengthwise in the frame and connected to a part of the carrying means and supporting said means, a spring on the rod 105 and bearing against said part, a detent to detachably hold the plunger rod in retracted position, a movable rack arranged to act against an abutment on and retract the plunger rod, a gear intermeshed with said 110 rack, and a handle for moving said gear.

6. The combination in a reel, of coil carrying means capable of expansion and contraction, a frame, a toothed plunger rod 115 movable lengthwise in the frame and connected to a part of the carrying means and supporting said means, a spring on the rod and bearing against said part, and a detent to detachably hold the plunger rod in retracted position; the said carrying 120 means being also rotatable about the rod, and the spring serving when tensioned to exert a braking action on the carrying means.

7. In a reel, the combination of coil 125 carrying means capable of expansion and contraction, a frame, a toothed plunger rod connected to and supporting the carrying means, a spring tending to contract the carrying means, a detent to detachably hold 130

the rod in retracted position, a movable rack to retract the rod, a gear intermeshed with the rack, a handle connected to said gear, and a spring to restore said gear to normal position.

8. In a reel, the combination of coil carrying means capable of expansion and contraction, a frame, a toothed plunger rod connected to and supporting the carrying means, a spring tending to contract the

carrying means, a detent to detachably hold the rod in retracted position, a movable rack to retract the rod, a gear intermeshed with the rack, a wheel fixed to the gear, a cable on said wheel, means to guide said cable, 15 and a handle on the cable.

In testimony whereof we affix our signatures.

DALRIDGE B. BEAVERS.
PATRICK D. BEAVERS.
